WITNESS:

UNITED STATES PATENT OFFICE

2,016,187

SLED RUNNER SHOE

Joseph Vincent, Pittsburgh, Pa.

Application March 26, 1934, Serial No. 717,466

3 Claims. (Cl. 280—28)

This invention relates to sleds, and its general object is to provide runner attachments in the form of shoes that are adapted to be clamped to the sled runners after the latter become worn, or 5 to new sled runners, to protect the same, as well as to prolong the life thereof.

Another object of the invention is to provide sled runner shoes that can be fixed to the runners in an easy and expeditious manner, are 10 simple in construction, inexpensive to manufacture and extremely efficient in use and service.

This invention also consists in certain other features of construction and in the combination and arrangement of the several parts, to be hereinafter fully described, illustrated in the accompanying drawing and specifically pointed out in in 15 the appended claims.

In describing my invention in detail, reference will be had to the accompanying drawing wherein 20 like characters denote like or corresponding parts throughout the several views, and in which:

Figure 1 is a side elevation showing the application of one form of my invention attached to a sled.

25 Figure 2 is a sectional view taken approximately on line 2—2 of Figure 1, looking in the direction of the arrows.

Figure 3 is a sectional view taken approximately on line 3—3 of Figure 1, looking in the 30 direction of the arrows.

Figure 4 is a perspective enlarged view of a portion of the shoe.

Figure 5 is a similar view of a portion of a modified form.

35 Referring to the drawing in detail, the letter A indicates a sled of a well known construction and which includes substantially T-shaped cross sectional runners B.

In the form of the invention as disclosed in 40 Figures 1 to 4 inclusive, it will be noted that the shoes for the runners B each include an elongated base portion 1 with flanges 2 formed on the longitudinal edges thereof and which are bent in clamping engagement with the upper surface 45 of the base of the runners B, as best shown in Figure 3 of the drawing.

The forward portions of the shoes are curved 50 upwardly in order to follow the curvature of the forward portions of the runners B, and in order to provide the curved forward portions for the shoes, it will be noted that the flanges 2 for a portion of their length are slit transversely so as to facilitate the bending of the shoes as will be apparent.

55 Cooperating with the flanges 2 for securing the

shoes to the runners B, there are clamps which are secured to the forward ends of the curved forward portions of the shoes, and these curved forward portions are indicated by the reference numeral 3. One clamp is provided for each shoe and each clamp includes a base 4 that is provided with a seat 5, the latter being received into an opening 6 arranged centrally in the base portion of the curved forward portion of its shoe, and formed with the base of the clamp and extending 10 in curved formation therefrom are arms 7 which engage the flanges 2, and thence extend into upright parallel portions 8 that engage the sides of its runner. The arms 7 terminate in apertured ends that are arranged in contacting engagement and passing through the apertures 15 thereof is a bolt and nut connection 9.

In Figure 5 I have illustrated a modified form of my invention which includes a base 10, the latter being of a length substantially coextensive 20 with the length of the runner, and the base portion 10 is likewise provided with a curved forward portion to follow the curvature of the runner. A clamp of the type shown in the first mentioned form may be used for securing the 25 curved forward portion of the modified form to the runner, while the remaining portion of the base 10 of the modified form is secured to the runner through the instrumentality of spring arms 11, that are formed integral with the side 30 edges of the base and extend inwardly in curved formation and terminate in upturned confronting ends as shown.

While I have shown a single pair of spring arms 11, it is of course to be understood that any number of pairs may be employed throughout the 35 length of the base 10, and while I have referred to the arms 11 as being spring arms or in other words of resilient nature, these arms may be substantially rigid and bent about the runners. 40

From the above description and disclosure of the drawing, it will be obvious that I have provided shoes for sled runners that can be applied to old or new sleds, in an easy and expeditious manner, and the shoes will protect the runners 45 and materially prolong the life thereof.

It is thought from the foregoing description that the advantages and novel features of my invention will be readily apparent.

I desire it to be understood that I may make 50 changes in the construction and in the combination and arrangement of the several parts, provided that such changes fall within the scope of the appended claims.

What I claim is:

1. A protector shoe for sled runners comprising an elongated base shaped to follow the longitudinal shape of the base portion of a runner, means extending laterally from the longitudinal edges of the shoe base to be clamped about the runner, a clamp shaped to follow the transverse shape of the shoe and runner and to be clamped about the same for cooperation with said means for securing the shoe to the runner, securing means at the upper portion of the clamp, said shoe base having an opening therein, and a seat on the clamp to be received in the opening for cooperation with the securing means to hold the clamp against movement.
- 15 2. A protector shoe for sled runners comprising a base, inwardly bent flanges formed on the longitudinal edges of said base and being co-extensive with the length thereof, a curved forward portion for said shoe to follow the curvature of the forward portion of a runner, said flanges at the curved portion of the shoe being

slit transversely to facilitate the bending of the shoe about the forward portion of the runner, a clamp at the outer end of the curved portion and connected with respect to the runner at its upper portion and with the shoe at its lower portion, and said clamp cooperating with the flanges for securing the shoe to the runner.

5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

JOSEPH VINCENT.
